UNITED STATES PATENT OFFICE.

ROBERT BROOKS, OF ASHTON-ON-MERSEY, AND ALAN PRIESTLEY, OF STRETFORD, ENGLAND, ASSIGNEES TO WESTINGHOUSE ELECTRIC AND MANUFACTURING COMPANY, A CORPORATION OF PENNSYLVANIA.

PNEUMATIC CONTROL APPARATUS.

Application filed July 13, 1922, Serial No. 574,721, and in England July 18, 1921.

Our invention relates to apparatus for controlling the raising and lowering of the trolley in systems of electric traction with overhead conductors and in particular to systems of this nature in which a number of trolleys are to be simultaneously operated throughout an electric train.

For this purpose, it is usual to provide devices operated by means of compressed air the supply of which is controlled by electrically operated valves located in the trolley cars or locomotives and controlled by a suitable arrangement of master switches and train lines. Where the current for operating the master switches is obtained from an auxiliary motor generator, which is driven by current supplied from the main supply conductors or trolley wires, a plain solenoid-operated valve will give rise to trouble in the event of either a breakdown of the auxiliary generator or drop in the potential of the main conductors as, under these circumstances, the trolleys will be automatically lowered and thus prevent any current being supplied from the main conductors.

One of the objects of our invention is to provide means for so controlling the supply of compressed air to the trolley raising and lowering apparatus that, when the controlling devices are moved into either the "raised" or "lowered" positions, they will remain in the position to which they were last moved, until positively moved to the other position.

Another object of our invention is to simplify and improve generally, the construction and operation of fluid-actuated devices.

To enable the invention to be clearly understood, it will now be described with reference to the accompanying drawings, in which

Fig. 1 is a view, in sectional elevation, of the apparatus which I employ for governing the supply of compressed air to the operating cylinder of a trolley, and

Fig. 2 is an electrical diagram of control circuits for operating the valve device shown in Fig. 1.

The valve device comprises a suitable casting 1 containing the inlet port 2 connected to a supply of compressed air (not shown) and a port 3 connected by a pipe with the cylinder which contains the usual piston that raises the trolley through suitable link

and lever connections (also not shown). 55 Within the casing 1 is disposed an inlet valve 4 having a webbed stem 5 extending through the valve seat 6 with which it cooperates. The valve 4 operates within an inlet pocket 7 in the casing 1 and is normally pressed upon the seat 6 by means of a spring 8 fitted within a recessed cap 9 screwed into the end of the casing 1 according to well known practice.

An exhaust valve 10 is also located within 65 the casing 1, in axial alinement with the inlet valve 4, and is provided with a webbed stem 11 extending through the seat 12 with which said valve cooperates. The stems 5 and 11 of the inlet and exhaust valves, respectively, are of such length that, when the exhaust valve is closed its stem engages the stem of the inlet valve and opens the latter to the full extent so as to admit air to the trolley operating cylinder. On the other hand, when the inlet valve 4 is closed the exhaust valve 10 is fully opened to permit the air in the trolley-operating cylinder to escape through an exhaust port 13 in the back 70 of the casing 1.

In axial alinement with the inlet and exhaust valves, is arranged a piston 14 that operates in a cylinder 15 in the lower part of the casing 1. The piston 14 is provided with an upwardly extending stem 16 that engages the underside of the exhaust valve 10. A compression spring 17 is arranged on the upper side of the piston 14 so that the latter is normally biased to its lower position. 80

Attached to the lower end of the casing 1 is a casting 18 containing the electro-pneumatic mechanism for admitting compressed air to, and releasing it from beneath the piston 14. Such electro-pneumatic mechanism comprises an admission valve 19 normally closed upon a seat 20 by means of a spring 21. As will be observed, the valve 19 may be actuated to control communication between a pipe 23, which leads to a source of supply of compressed air (not shown), and a passage 24 provided in the casting 18. The passage 24 communicates with a passage 25, through check valve 26 that is normally pressed against its seat 27 by a spring 28. The passage 25 communicates with the space 29 beneath the piston 14. The passage 25 and, consequently, also the space 29 95

have communication through a passage 30 with a chamber 31 that contains a valve 32 which is normally pressed by a spring 33 upon a seat 34, the valve 32, when opened, placing the passage 30 in communication with an exhaust port 35.

The admission valve 19 and the exhaust valve 32 are operated electro-magnetically, one of the electromagnetic mechanisms being shown in section, at the right-hand side of Fig. 1, by way of example. Said mechanism comprises a coil 36 having suitable terminals 37 and wound upon a tubular iron core 38 through which passes a pin 39 which rests upon the upper end of the stem of the valve 32. The pin 39 extends above the upper end of the core 38 and an armature 40 rests upon the upper end of the pin 39.

Upon energization of the coil 36, the armature 40 is attracted by the core 38 so that the pin 39 is biased downwardly and, engaging the valve 32, opens the latter, thereby placing the space 29 beneath the piston 14 in communication with the exhaust port 35. An external button 41, extending through a casing 42 which covers the electromagnetic mechanism, is provided to enable the valve 32 to be manually opened.

The admission valve 19 is operated in an exactly similar manner but, in addition, the valve operating pin 43 is itself provided with a valve face 44 adapted to engage a seat 45 when the coil 36a is energized, that is to say, while the admission valve 19 is normally closed by means of the spring 21, the auxiliary valve 44 is normally open to place the passage 24 in communication with an exhaust port 46.

A by-pass for compensating for loss of pressure in the chamber 29 is indicated at 47 and is conveniently provided in the wall of the casing 1, to place the space above the exhaust valve 10 in communication with the space 29. A screw pin 48 is provided for adjusting the sectional area of the by-pass 47, for the purpose of regulating the relative pressure upon the two sides of the piston 14.

The operation of the valve device is as follows: When it is desired to raise the trolley into contact with the trolley conductor, the coil 36a is energized by the closure of a suitable switch or the button 41 may be depressed by hand, so that compressed air from the pipe 23 is admitted through the valve 19 to the passage 24 which is now cut off from the exhaust port 46 by closure of the auxiliary valve 44. The compressed air traverses the passage 24 and passes the check valve 26 and traverses the passage 25 into the chamber 29, to force the piston 14 upwardly, the exhaust valve 32 being at this time closed. The piston thus closes the exhaust valve 10, and the stem 11 of this valve engages the stem 5 of the normally

closed inlet valve 4 and opens the latter to admit compressed air through the port 2 from the supply to the port 3 connected with the cylinder which operates the trolley whereby the latter is raised.

The inlet valve 19 may be then permitted to close. When this occurs, the valve 44 exhausts the passage 24 but the pressure is retained within the chamber 29 behind the piston 14 by reason of the non-return valve 26. Compressed air is admitted from the space above the exhaust valve 10 through the by-pass 47, thereby compensating for any leakage of pressure past the piston 14 or elsewhere in the auxiliary pneumatic control system. It will thus be seen that, when the trolley has been raised, it will be maintained in its elevated position, irrespective of any electrical circuits which may fail.

In order to lower the trolley, the right-hand coil 36 is energized, or the button 41 depressed, so that the valve 32 is opened to exhaust the pressure behind the piston 14 to atmosphere through the passage 30 and exhaust port 35. The piston 14 is then forced downwardly by pressure upon the valve 10, assisted by the spring 17. The exhaust port 35 is of relatively larger area than the effective area of the by-pass 47.

Upon the piston 14 moving down, the inlet valve 4 is closed to cut off the pressure from the supply connected to the port 2 and, at the same time, the air in the operating cylinder of the trolley is exhausted through the port 3, the valve 10 and the exhaust port 13 to atmosphere. This having occurred and the inlet valve 4 being closed, no pressure can be supplied beneath the piston 14 by the by-pass 47. The coil 36 may then be de-energized to permit the valve 32 to close in readiness for again operating the device for raising the trolley.

The extent of the by-pass is regulated by an adjusting screw 48, which is necessary, since, if the opening be too large, the opening of the chamber 29 to exhaust through the valve 32 may not result in a sufficient reduction of pressure below the piston 14 to effect the proper opening of the exhaust valve 10. On the other hand, if the by-pass opening is too small and the piston 14 is somewhat worn or leaky, the valve 10 would tend to open to the exhaust instead of remaining properly closed. The spring 17 is provided to insure that the valve 10 and also the piston 14 will always return to the exhaust position when the pressure within the space 29 is released.

In trains where a number of trolleys are to be simultaneously operated, the electro-magnet coils 36-36a of the several trolleys may be energized from circuits extending throughout the length of the train. Referring to Fig. 2, wherein two valve devices in accordance with the invention are

indicated at 1-1, the main negative conductor 51 and selection conductors 52 and 53 pass throughout the length of the train. One end of each of the trolley raising and 5 lowering coils 36a-36 is connected to the conductor 51 while the other ends of the said coils are respectively connected to the selection conductors 52 and 53.

In each motorman's compartment of the 10 train is disposed a two-way switch 54, the blade of which is connected to the positive main train bus 50. The switch 54 normally occupies its "off" position, being thus biased by means of a spring or otherwise 15 and it may be moved by hand into engagement with either of the contact members 55 or 56, to effect the connection of the trolley raising and lowering coils 36a-36 to the main bus conductors 50-51. With this 20 arrangement, the operation of any one of the switches 54 will raise or lower all the trolleys of the train.

In the event of the auxiliary electric supply being inoperative for any reason, 25 such as when no trolley is elevated and in contact with the trolley wire, the raising of all the trolleys may be effected by pressing the left-hand button 41 of any one of the valve devices. In this manner, compressed 30 air is admitted to that valve device, the button of which has been depressed so that the trolley of that particular device is raised and thereby establishes the auxiliary supply which will then permit the remaining trolleys, if any, to be raised by the operation of 35 any one of the switches 54.

It will be understood that various modifications may be made in the construction of 40 the valve devices and in the arrangement of the control circuits therefor, without departing from the scope of the invention.

We claim as our invention:

1. In combination, a chamber having an 45 inlet opening and an outlet opening, valves for controlling said openings, said valves being adapted to close one opening when they open the other, a piston for operating the valves, a cylinder in which the piston is slidably mounted, means for supplying fluid 50 pressure to the piston to effect its operation in one direction to close the exhaust opening, a by-pass for connecting the chamber with the cylinder to equalize the pressure in the cylinder and chamber to maintain the piston in a predetermined position.

2. In combination, a chamber having an 55 inlet opening and an outlet opening, valves for controlling said openings, said valves

being adapted to close one opening when they open the other, a piston for operating 60 the valves, a cylinder in which the piston is slidably mounted, means for supplying fluid pressure to the piston to effect its operation in one direction to close the exhaust opening, a by-pass for connecting the chamber 65 with the cylinder to equalize the pressure in the cylinder and chamber to maintain the piston in a predetermined position and means for controlling the flow of fluid through the by-pass.

3. In combination, a chamber having an inlet opening and an outlet opening, valves for controlling said openings, said valves being adapted to close one opening when they open the other, a piston for operating 70 the valves, a cylinder in which the piston is slidably mounted, means for supplying fluid pressure to the piston to effect its operation in one direction to close the exhaust opening, a by-pass for connecting 75 the chamber with the cylinder to equalize the pressure in the cylinder and chamber to maintain the piston in a predetermined position, means disposed for independent operation to release the pressure on the piston and means energized by the movement of the piston under the influence of fluid pressure cooperative to move the piston in the opposite direction.

4. The combination with a passageway 80 for fluid under pressure and a valve for controlling the admission of fluid thereto, of an exhaust valve for said passage, a fluid-operated piston for controlling the movements of the said valves, means for 85 admitting fluid to the rear of the piston for actuating the same, and a by-pass of restricted area for establishing communication between the said passage and the rear of the piston when the said control valve is 90 in open position.

5. The combination with a fluid pressure chamber, of a valve for controlling the admission of fluid thereto, an exhaust valve therefor, fluid pressure operated means for 95 normally maintaining the valves in open and closed positions respectively, and means for utilizing pressure from the said chamber to assist in maintaining the said valves 100 in their normal positions.

In testimony whereof, we have hereunto 105 subscribed our names this 23rd day of June, 110 1922.

ROBERT BROOKS.
ALAN PRIESTLEY.
